UNITED STATES PATENT OFFICE

2,153,817

MUSICAL INSTRUMENT

Aloysius S. Terhaar, Lemon Grove, Calif.

Application December 16, 1936, Serial No. 116,147

4 Claims. (Cl. 84—376)

My invention relates to a musical instrument, more particularly a musical instrument having some of the characteristics of an accordion and some of the characteristics of a harmonica, and the objects of my invention are:

First, to provide a musical instrument which readily harmonizes with a harmonica;

Second, to provide a musical instrument of this class which readily harmonizes with an accordion;

Third, to provide a musical instrument which has some of the characteristics of both the accordion and harmonica;

Fourth, to provide a musical instrument of this class which may be used by the player as his own accompaniment of a harmonica or other similar instruments;

Fifth, to provide a musical instrument of this class with a bellows which operates reeds with both the in-going and out-going air;

Sixth, to provide a musical instrument which is new and novel; and

Seventh, to provide a musical instrument of this class which is very simple and economical of construction, easy to operate, durable, and efficient.

With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application in which:

Figure 1 is a top or plan view of my musical instrument; Fig. 2 is a longitudinal sectional view from the line 2—2 of Fig. 1; Fig. 3 is a side elevational view and Fig. 4 is an enlarged fragmentary sectional view from the line 4—4 of Fig. 1.

Similar characters of reference refer to similar parts and portions throughout the several views of the drawing:

The upper plate 1, lower plate 2, bellows fabric 3, spring 4, air controlled casing 5, partition 6, screws 7, reeds 8 and 9, keys 10 and 11, harmonica holders 12, and tape 13 constitute the principal parts and portions of my musical instrument.

The upper plate 1 may be of varying sizes, but is substantially three inches wide by ten inches long and may be made of metal or wood. The lower plate 2 is similar to the plate 1 and may be made of metal or wood. It is preferred to make the lower plate slightly shorter as the lower plate is used substantially on a horizontal plane when

in operation, while the upper plate is on an incline from the horizontal as shown best in Figs. 2 and 3 of the drawing.

Mounted on the upper sides of the plates 1 and 2 and at the opposite ends is the bellows fabric 3 providing an air tight chamber between the plates 1 and 2, it being noted that this fabric is wider at the one end as shown best in Figs. 2 and 3 of the drawing. Secured at the larger end is a piece of tape 13, which is secured to the ends of both the members 1 and 2 and prevents the members 1 and 2 from spreading too far apart, thus insuring that the bellows fabric 3 turns inwardly with the movement of the members 1 and 2 toward each other. Positioned some distance from this large end between the members 1 and 2 is a compression spring 4 which tends to move the members 1 and 2 apart at the larger end. Mounted across the outer side of the upper end of the plate 1 is a pad 1a which forms a cushion for the fingers of the operator and the end of the member 2 rests on the palm of the hand and thumb base.

Secured on the inner or lower side of the member 1 at the smaller end is a casing 5 which serves to control the flow of air to and from the interior of the instrument. This casing extends across the member 1 and is provided with a partition 6 interposed between the side 5a of the casing 5 and the plate 1 as shown best in Figs. 2 and 4 of the drawing and spaced by means of partitions 1d and 5d and held together by screws 7, thus dividing the casing 5 into a plurality of compartments. In this case I have shown eight, but may be more or less as desired. Each of these compartments is provided with an opening 1b through the plate 1 and each compartment is also provided with another opening 1c through the plate 1. In the openings 1c are provided key members 10 and 11 which are provided with stems 10a and 11a which are provided with valves 10b and 11b on their extended ends. Interposed between the key members 10 and the partition 6 are compression springs 10c and 11c which tend to hold the valves 10b closed, it being noted that in Fig. 2 the valve 10b is shown closed while the valve 11b is shown opened. These valves cover openings 5b in the casing member 5. The partition 6 is provided with slots 6a shown best in Fig. 4 of the drawing over which are positioned reeds 8 and 9 on opposite sides so that when the air passes outwardly through the slots 6a, the reeds 8 are operated and when the air passes inwardly through the reeds 6a, the reeds 9 are operated.

Secured on the inner or lower side of the member 1 at the smaller end is a casing 5 which serves to control the flow of air to and from the interior of the instrument. This casing extends across the member 1 and is provided with a partition 6 interposed between the side 5a of the casing 5 and the plate 1 as shown best in Figs. 2 and 4 of the drawing and spaced by means of partitions 1d and 5d and held together by screws 7, thus dividing the casing 5 into a plurality of compartments. In this case I have shown eight, but may be more or less as desired. Each of these compartments is provided with an opening 1b through the plate 1 and each compartment is also provided with another opening 1c through the plate 1. In the openings 1c are provided key members 10 and 11 which are provided with stems 10a and 11a which are provided with valves 10b and 11b on their extended ends. Interposed between the key members 10 and the partition 6 are compression springs 10c and 11c which tend to hold the valves 10b closed, it being noted that in Fig. 2 the valve 10b is shown closed while the valve 11b is shown opened. These valves cover openings 5b in the casing member 5. The partition 6 is provided with slots 6a shown best in Fig. 4 of the drawing over which are positioned reeds 8 and 9 on opposite sides so that when the air passes outwardly through the slots 6a, the reeds 8 are operated and when the air passes inwardly through the reeds 6a, the reeds 9 are operated.

Secured on the inner or lower side of the member 1 at the smaller end is a casing 5 which serves to control the flow of air to and from the interior of the instrument. This casing extends across the member 1 and is provided with a partition 6 interposed between the side 5a of the casing 5 and the plate 1 as shown best in Figs. 2 and 4 of the drawing and spaced by means of partitions 1d and 5d and held together by screws 7, thus dividing the casing 5 into a plurality of compartments. In this case I have shown eight, but may be more or less as desired. Each of these compartments is provided with an opening 1b through the plate 1 and each compartment is also provided with another opening 1c through the plate 1. In the openings 1c are provided key members 10 and 11 which are provided with stems 10a and 11a which are provided with valves 10b and 11b on their extended ends. Interposed between the key members 10 and the partition 6 are compression springs 10c and 11c which tend to hold the valves 10b closed, it being noted that in Fig. 2 the valve 10b is shown closed while the valve 11b is shown opened. These valves cover openings 5b in the casing member 5. The partition 6 is provided with slots 6a shown best in Fig. 4 of the drawing over which are positioned reeds 8 and 9 on opposite sides so that when the air passes outwardly through the slots 6a, the reeds 8 are operated and when the air passes inwardly through the reeds 6a, the reeds 9 are operated.

Secured on the inner or lower side of the member 1 at the smaller end is a casing 5 which serves to control the flow of air to and from the interior of the instrument. This casing extends across the member 1 and is provided with a partition 6 interposed between the side 5a of the casing 5 and the plate 1 as shown best in Figs. 2 and 4 of the drawing and spaced by means of partitions 1d and 5d and held together by screws 7, thus dividing the casing 5 into a plurality of compartments. In this case I have shown eight, but may be more or less as desired. Each of these compartments is provided with an opening 1b through the plate 1 and each compartment is also provided with another opening 1c through the plate 1. In the openings 1c are provided key members 10 and 11 which are provided with stems 10a and 11a which are provided with valves 10b and 11b on their extended ends. Interposed between the key members 10 and the partition 6 are compression springs 10c and 11c which tend to hold the valves 10b closed, it being noted that in Fig. 2 the valve 10b is shown closed while the valve 11b is shown opened. These valves cover openings 5b in the casing member 5. The partition 6 is provided with slots 6a shown best in Fig. 4 of the drawing over which are positioned reeds 8 and 9 on opposite sides so that when the air passes outwardly through the slots 6a, the reeds 8 are operated and when the air passes inwardly through the reeds 6a, the reeds 9 are operated.

5   Mounted on the lower side of the plate 2 near the smaller end of the instrument and extending outwardly therefrom are harmonica holders 12 for supporting a harmonica or other mouth
10   5 operated instrument so that the operator of this instrument may play the harmonica in the usual manner supported in the supports 12 and accompany the same with applicant's musical instrument by holding the large end in the right hand and operating the bellows and holding the small end in the left hand and operating the keys with the fingers of the left hand, thus the instrument may be shifted longitudinally carrying with it the harmonica held in the holders 15 10 12, or the musical instrument may be operated independently of the harmonica.

20   Though I have shown and described a particular construction, combination, and arrangement of parts and portions, I do not wish to be limited 20 to this particular construction, combination, and arrangement, but desire to include in the scope of my invention, the construction, combination, and arrangement substantially as set forth in the appended claims.

25   Having thus described my invention, what I claim as new and desire to secure by Letters Patent is:

30   1. A musical instrument consisting of two flat smooth outer surfaced members forming a bellows, shaped and arranged to be positioned between the fingers and palm of one hand of the operator and operated by the fingers of the same hand, an air controlled casing positioned entirely on the inside of said bellows on the 35 inner side of one of said members, said casing provided with passages therein, reeds associated with said passages and keys extending outwardly through the upper side member and adapted to be operated for controlling the flow of air through 40 the passages past the reeds inside of said bellows.

2. A musical instrument consisting of two flat smooth outer surfaced members forming a bellows, shaped and arranged to be positioned be-

tween the fingers and palm of one hand of the operator and operated by the fingers of the same hand, an air controlled casing positioned entirely on the inside of said bellows on the inner side of one of said members, said casing provided 5 with passages therein, reeds associated with said passages and keys extending outwardly through the upper side member and adapted to be operated for controlling the flow of air through the passages past the reeds inside of said bellows, 10 said air control casing divided into a plurality of compartments and a control key for each compartment extending just slightly above the outer side of said bellows at one end thereof.

3. A musical instrument consisting of a pair 15 of plates in spaced relation with their one ends farther apart than at their other ends, said plates being substantially smooth and without any projection on their outer surface arranged to be grasped between the palm and finger of 20 one hand of the operator thereof, a bellows fabric enclosing the sides and ends between said plates, a plurality of air conducting compartments positioned entirely inwardly of said plates so that the outer surface of said plates are smooth and 25 unobstructed, and reeds associated with each of said compartments.

4. A musical instrument consisting of a pair 30 of plates in spaced relation with their one ends farther apart than at their other ends, said plates being substantially smooth and without any projection on their outer surface arranged to be 35 grasped between the palm and finger of one hand of the operator thereof, a bellows fabric enclosing the sides and ends between said plates, a plurality of air conducting compartments positioned entirely inwardly of said plates so that the outer surface of said plates are smooth and unobstructed, reeds associated with each of said compartments, and keys for separately controlling the flow of air through said compartments 40 extending outwardly a slight distance through the wall of one of said plates.

ALOYSIUS S. TERHAAR.
